MARINE STOKER

William H. R. Marsden, Erie, Pa., assignor, by
mesne assignments, to The Standard Stoker
Company, Inc., New York, N. Y., a corporation
of Delaware

Application May 24, 1932, Serial No. 613,231

4 Claims. (Cl. 110—101)

This invention relates to stokers for use in firing the furnaces of a boiler such as the furnaces of the well known Scotch boiler used in maritime service, and has for its principal object the provision of a stoker which feeds fuel to each furnace of a boiler, the stoker comprising a fuel transfer conveyor receiving fuel from the bottom of the fuel bunker, a single upright elevator receiving fuel from said transfer conveyor and a plurality of devices for conducting the fuel from said single upright elevator to each of said furnaces.

It is also an object of this invention to provide a stoker for feeding fuel to each furnace of a boiler, the stoker including a single upright fuel elevator which elevates the fuel to a point sufficiently high above the firebed of each of the furnaces to cause the fuel to drop by gravity through suitable tubes from such point to the stoker fuel distributors. This phase of the present invention also contemplates the provision of a novel fuel apportioning mechanism whereby the amounts of fuel delivered by the fuel elevator to each of the tubes may be readily and positively varied by the stoker operator.

Further objects of this invention reside in the novel arrangements of parts and in their relation one with another and also in the provision of a novel fuel bin and stoker trough arrangement which permits the flow of fuel into the trough to be readily controlled and at the same time providing access to the stoker conveying mechanism.

On the drawings, Figure 1 is a vertical longitudinal fragmentary section through a boiler showing a furnace thereof in central vertical-longitudinal fragmentary section, with the invention shown in elevation, a portion of which has been broken away.

Figure 2 is a plan view of the structure shown in Figure 1, the boiler and fuel bunkers being shown in fragmentary section and the grates omitted.

Figure 3 is a sectional view taken on the line 3—3 of Figure 1, showing the boiler in front elevation,

Figure 4 is a section taken on the line 4—4 of Figure 2,

Figure 5 is a fragmentary section taken on the line 5—5 of Figure 1,

Figure 6 is an enlarged sectional view taken on the line 6—6 of Fig. 3,

Figure 7 is a plan view of the structure shown in Figure 6,

Figure 8 is a front elevation of the fuel distributor, and

Figure 9 is a plan view of the structure shown in Figure 8.

Referring to the figures which illustrate the preferred embodiment of this invention, the boiler room of a vessel is shown at 10 and its floor at 11 above which are mounted the fuel bunkers 12, 12a, each provided with front and rear walls. A boiler for generating steam is shown at 13 and is preferably of the Scotch type comprising a drum 14 and the cylindrical furnaces 15 and 16. Each of the furnaces 15 and 16 is provided with a fire grate 17 and access doors such as 18 through which manual firing of each furnace may be effected.

A suitable stoker mechanism S conveys fuel from the fuel bunker 12 into the furnaces 15 and 16 in a manner which will now be described. The stoker S includes a fuel transfer conveyor 19 which receives fuel from the bunker 12 through its open mouthed trough 20. The fuel transfer conveyor 19 preferably is mounted wholly beneath the floor 11 in order to allow freedom of movement in the boiler room 10. A conveyor screw 21 is mounted within the transfer conveyor 19 and urges fuel forwardly into the hopper 22 of the fuel elevator 23, which elevator comprises the upright casing 24 secured to the upper portion of the hopper 22. The elevator 23 is preferably disposed on the vertical center line of the boiler 13 and has a fuel elevating screw 25 mounted therein for moving the fuel upwardly as the same is delivered into the hopper by the conveyor screw 21. Surmounting the upright casing 24, is the tubular extension 26 which terminates a sufficient distance above the fuel distributors 32, 33 that tube members such as 66, 67 may be utilized for conducting fuel by gravity to each of said distributors. The fuel distributors 32 and 33 extend forwardly from the lower outward extremities of the tube members 66 and 67 and enter the furnaces 15 and 16 respectively at points above the level of the fire grates therein to insure proper distribution of the fuel thereover.

The means for driving the screw conveyors of the stoker S include a prime mover 44 which drives the gearing 45 through the forwardly extending shaft 46 for operating the elevating screw 25. Extending rearwardly from the prime mover 44 and operatively connected thereto, is a shaft 47 which transmits power to gearing (not shown), housed in the casing 48 at the rear of the open

mouthed trough 20 for driving the conveyor screw 21 mounted therein.

By referring to Figures 1 and 2, it will be apparent that the fuel bunkers 12, 12a are separated from each other by the laterally spaced side walls 49, 50, thereby providing an alcove 51 between these fuel bunkers. The floor 11 of the boiler room is apertured in this alcove and a removable plate 52 is placed over the gear casing 48 whereby access thereto may be conveniently had by removing the plate 52.

Fuel falls by gravity from the bunker 12 through the vertical aperture 53 in the side wall 49 and thence through the opening 54 in the floor 11 into the open mouthed trough 20. A hood 55 which is hinged with the wall 49 as at 55a surrounds the opening 54 and prevents the fuel from overflowing onto the floor 11. A vertically slideable gate 56 which is normally suspended in its upper position by a hook 57, serves as a closure for the aperture 53.

Whenever it is desirable or necessary to gain access to the interior of the trough 20, the gate 56 is permitted to slide downwardly thereby preventing further admission of fuel into the trough. The stoker is then operated for a time sufficient to empty the trough 20, after which the hood 55 may be raised and the necessary inspection or repair of the trough and the conveying mechanism made.

If desirable or necessary, the fuel bunker 12a may also be provided with a hinged hood and gate such as used in connection with the fuel bunker 12, and in this manner, the bunker 12a will feed fuel into the trough 20 when the supply of fuel in the bunker 12 has become exhausted. It is understood, that in those instances wherein a battery of boilers is used for generating steam, the fuel bunkers are then provided with the required number of alcoves under each of which a trough is mounted to receive fuel from the bunkers as heretofore mentioned, and which trough transfers fuel to the elevator of its respective boiler.

The elevating screw 69 terminates below the upper portion of the tubular extension 65 so that a more or less columnar formation of fuel will be conducted to the delivery mouth 68 of the tubular extension with which common mouth the diverging tube members 66, 67 communicate.

In order that the delivery of the fuel to each furnace may be effectively controlled, the upper portion of the tubular extension 65 is provided with a counter-bored portion 70, which receives a fuel control head 71 having an aperture 80 therein which is normally in approximate register with the mouth 68. A portion of the head 71 is serrated as at 72 to form a segment of a crown gear 73, which is engaged by a crown pinion 74. A rod or shaft 75 carries the pinion 74 and is received in suitable bearings 76, 77 along the side of the upright elevator casing 24 and the tubular extension 65. By turning the handwheel 78, which is within easy reach of the stoker operator, the pinion 74 will rotate the gear segment 73 and thus cause the control head 71 to close off the mouth 68 in any suitable degree depending upon the amount of rotation, thus varying the amounts of fuel delivered to each of the tube members 66, 67.

In order that the control head 71 may be easily moved, the tubular extension is flanged as at 79 to form a race 80 on which rest the rollers such as 81 of the control head 71. In this manner, the control head is supported exteriorly of the tubular extension and is thus easily rotated. From the foregoing description, it is apparent

that a stoker has been devised which is especially useful for installation in connection with a boiler having a plurality of furnaces. Furthermore, the stoker occupies but little space in the boiler room and may be readily controlled by the novel construction of the fuel dividing means. The arrangement of applicant's fuel bunkers in relation with the stoker trough will also prove to be advantageous in that the fuel conveying mechanism is readily accessible for the purpose of repairs or inspection.

I claim:

1. In combination with a boiler having a plurality of furnaces, each provided with a fire grate, a floor below the level of said furnaces, and a fuel bunker disposed above said floor, a stoker comprising a fuel transfer conveyor mounted beneath said floor and receiving fuel from said bunker, an upright elevator adjacent said boiler, said elevator at its lower end receiving fuel from said transfer conveyor, a fuel distributor for each furnace, each of said fuel distributors entering into its respective furnace at a point above the fire grate thereof, said upright elevator including a casing and a tubular extension surmounting said casing and having a fuel delivery opening, a plurality of diverging tube members extending downwardly from and communicating with the fuel delivery opening of said tubular extension and delivering to respective fuel distributors, a screw within the casing for elevating fuel through said casing and along said tubular extension and delivering fuel into each of said tube members, said screw terminating below the upper portion of said tubular extension, a rotatable control head comprising a cylindric wall mounted within the upper portion of said tubular extension and closely fitting against the inner wall thereof, said head being provided with an opening adapted to register with the discharge opening of said tubular extension, and means for rotating said head to bring the opening therein into register or out of register with the opening in said tubular extension, for controlling the delivery of fuel therefrom.

2. In combination with a boiler having a plurality of furnaces, and a source of fuel supply, a stoker for feeding fuel to the furnaces comprising a fuel transfer conveyor leading from the source of fuel supply, a single upright elevator receiving fuel from said transfer conveyor and including a tubular extension at its upper end having an aperture therein, a plurality of outwardly and downwardly extending feed devices communicating with said tubular extension through said aperture and leading respectively to said furnaces, a rotatable control head comprising a cylindric wall mounted within the upper portion of said tubular extension and closely fitting against the inner wall thereof, said head being provided with an opening adapted to register with the discharge opening of said tubular extension, and means for rotating said head to bring the opening therein into register or out of register with the opening in said tubular extension, for controlling the delivery of fuel therefrom.

3. In combination with a boiler having a plurality of furnaces, a stoker for feeding fuel into each of said furnaces, said stoker including a fuel elevator having a tubular extension at its upper end provided with an aperture therein and a plurality of outwardly and downwardly extending feeding devices communicating with said tubular extension through said aperture and lead-

ing respectively to said furnaces, a rotatable control head comprising a cylindric wall mounted within the upper portion of said tubular extension and closely fitting against the inner wall thereof, said head being provided with an opening adapted to register with the aperture of said tubular extension, and means including a gear and segment for rotating said head to bring the opening therein into register or out of register with the aperture of said tubular extension, for controlling the delivery of fuel therefrom.

5 4. In combination with a boiler having a plurality of furnaces, a source of fuel supply, a stoker for feeding fuel to the furnaces comprising a fuel transfer conveyor leading from the source of fuel supply, an upright conduit receiving fuel from said transfer conveyor and provided near its upper end with an opening in one side, a conveyor screw in said conduit for elevating fuel

therethrough, a plurality of tubular casings each communicating at one end with the opening in said upright conduit for receiving fuel therefrom and at the other end communicating with one of said furnaces for delivering fuel thereto, 5 a control head comprising a cylindric wall mounted within the upper portion of said upright conduit and fitting closely against the inner wall thereof, said head being provided with an opening adapted to register with the opening in said upright conduit, and means for rotating said cylindric wall along the inner wall of said upright conduit and across the area of communication between said tubular casings and said upright conduit for controlling the delivery of 10 fuel from said upright conduit into said tubular casings. 15
